MICHAEL H. FEEHAN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

FILLING STOP MOTION FOR LOOMS

Application filed May 18, 1928. Serial No. 278,902.

This invention relates to improvements in filling stop motions for looms and it is the general object of the invention to provide a motion having provision for reducing the pressure of the filling fork tines as they engage the filling.

The invention relates more particularly though not necessarily to so-called center filling stop motions wherein the fork which engages the weft is located between the selvages of the cloth being woven. Because of its position there is a tendency for the fork to stretch the filling between the selvages, so that at the time of beat-up the cloth located in line with the fork may be kinky or have a different appearance from the remainder of the cloth. It is an important object of my present invention to provide means for lowering the fork upon the filling by first exerting a force sufficiently strong to insure downward movement of said fork and then reducing the force so that there will be little or no tendency to produce undue slackness in the filling.

The so-called No. 9 or Knowles center stop motion employs a cam plate fixed with respect to the breast beam of the loom and adapted for cooperation with a dagger supported by and moving with the lay. Said dagger is mounted for vertical movement relatively to the lay and is operatively connected to the tines of the fork, the dagger moving downwardly and forwardly during the forward beat of the lay to lower the fork on the filling. If filling is present the dagger will be supported so as to clear a knock-off lever, but if filling is absent the dagger will descend to a sufficient level to engage the lever to insure stopping of the loom.

It is a more detailed object of my present invention to associate with the connector between the dagger carrier and the fork element a movable weight which acts during the first part of the downward movement of the fork to insure movement of the latter toward the filling. As the fork descends the weight engages a stop by which it is supported so that the fork may continue to move downwardly with reduced force and exert a lessened pressure against the filling. While I

have described this feature of the invention in connection with the so-called No. 9 stop motion yet the principle set forth herein may be applied to the so-called No. 8 stop motion such as is used extensively on silk looms and is shown in Patent No. 376,776.

With these and other objects in view which will appear as the description proceeds, my invention resides in the combination and arrangement of parts hereinafter described and set forth in the claims:

In the accompanying drawings wherein one form of my invention is shown,

Fig. 1 is a vertical transverse section through the breast beam and lay and showing my filling stop motion in a position to permit continued running of the loom.

Fig. 2 is a detailed front elevation of the stop motion looking toward the lay in the direction of arrow 2, Fig. 1.

Fig. 3 is an enlarged elevation taken in the direction of arrow 3, Fig. 2, certain parts being in section.

Fig. 4 is a detailed horizontal section on line 4—4 of Fig. 3, and

Figs. 5 and 6 are views similar to a portion of the structure shown in Fig. 1, but with the parts in different positions.

Referring particularly to Fig. 1 I have shown the breast beam 10 of the loom frame as being provided with a bracket 11 from which extends a bearing 12 for the shipper shaft or rod 13. Said rod has secured thereto an arm 14 extending rearwardly and under a lug 15 cast usually as an integral part of the C-shaped knock-off lever 16. The lever is pivoted at 17 to a bracket 18 held in fixed position relatively to the breast beam and said lever abuts the lug 19 formed as part of the bracket 18, but extends above said lug as shown in Fig. 1.

Adjustably secured to the rear end of the bracket 18 is a cam plate 20 having a downwardly and forwardly extending face 21 the relative position of which may be varied with respect to the bracket 18 by means of a bolt 22. The face 21 is adapted for engagement with a dagger 23 held in a dagger carrier 24 pivoted as at 25 to a bracket 26 secured to the underside of the lay 27. The rear end of

said carrier may be counterweighted as at 28 and said carrier is free to move about stud 25 so that when occasion requires the dagger 23 may move downwardly low enough to engage that portion of the notch 29 in the C-shaped lever 16 which extends above the bracket 18.

Pivottally connected as at 30 to the dagger carrier 24 is a connector C the upper end of which is pivotally connected as at 31 to an arm 32 secured to a stub shaft 33 which as shown in Fig. 2 extends through a pair of spaced bearings 34. Said bearings may be formed as part of a plate 35 which may either be a part of the bracket 26 or a separate part secured to the lay 27. A tine carrying member 36 is located between the bearings 34 and by means of screws 37 supports and holds in position the tines 38 of the filling fork. The arm 32, stub shaft 33, element 36 and tines 37 constitute the fork element previously mentioned. The tines are adapted for movement into a well 39 formed in the upper part of the lay 27. Set screw 40 secures the member 36 to the stub shaft 33.

When the lay is in rearward position the dagger 23 is lifted to a relatively high position by the cam plate 20 so that the connector operating through the parts previously described raises the tines of the fork to the position shown in Fig. 5. As the lay advances the dagger will start to move down the cam face 21 as previously described.

The matter thus far described is of common construction with the exception of the connector C and is the so-called No. 9 or Knowles center stop motion such as is set forth in patent to G. F. Hutchins No. 560,036 to which reference may be had for further description of the manner in which counterclockwise movement of the C-shaped lever 16 will cause the lug 15 to depress the arm 14 and cause an angular movement of the shipper rod or shaft 13 to effect stopping of the loom. The structure already described forms no part of my present invention and may if desired be formed as shown in prior Patents No. 1,223,708 to McGuiness or 1,243,831 to Gagnon.

In carrying my present invention into effect I provide improved means for controlling the downward movement of the tines 38 and for reducing the force acting on said tines tending to move them into the well 39. By referring particularly to Fig. 3 it will be seen that I have formed the connector C with a lower flat part 50 having a reduced upper end 51 and provide the latter with threads 52 which extend into a head 53. The lower part 50 has shoulders 54 on which may rest one or more weights 55. Said weights can be assembled in the position shown in Fig. 3 by reason of the fact that the head 53 may be removed from the threads 52 to permit in-

sertion of the reduced ends 51 through the openings in said weights.

A stop 56 is formed preferably though not necessarily as shown in Fig. 4 with a pair of lugs 57 spaced apart a sufficient distance to accommodate the lower portion 50 and the bottom of the reduced portion 51. Said portion 50 extends freely between the lugs 57 as shown in dotted lines in Fig. 4 and said lugs are so proportioned and located as to engage the lowest weight 55 as the tines approach the end of their detecting movement.

In operation, the parts will be in the position shown in Fig. 5 with the shoulder 54 holding the weights 55 in raised position and the tines 38 up when the lay is in its rearward position. As the lay moves forwardly the dagger 23 will move downwardly, as previously described, to effect a lowering of the tines 38 and the connector C. During the downward movement of the latter the weights, which as will readily be understood are free to move or slide with respect to the end 51, are arrested by stop 56 so as to be held against further downward movement. The pressure tending to move the tines into the well 39 will, therefore, be considerably reduced and will be dependent merely upon the weight of the parts which continue to move as the weights 55 come to rest relatively to the lay.

I have shown herein three separate weights so that the pressure may be varied and I have shown the variation in the pressure brought to bear on the tines as being effected through the arresting of movement of weights, but I do not wish to be limited to the particular arrangement shown herein, as my invention contemplates in its broader aspects means to change a yielding pressure tending to lowering of the tines 38 toward the well 39.

From the foregoing it will be seen that I have provided a very simple device wherein a yielding device acts to move the tines 38 downwardly with sufficient force to insure a proper start in the downward movement of said tines, but that as said tines approach the filling the pressure is reduced so that there will be a diminished tendency on the part of the filling fork to produce undue and undesirable slack in the filling. It will further be seen that as the fork assumes the horizontal position where it would tend with greatest force to move downwardly by its own weight, the weights 55 are held against further control of the fork.

Having thus described my invention it will be seen that changes and modifications may be made therein by those skilled in the art without departing from the spirit and scope of the invention and I do not wish to be limited to the details herein disclosed, but what I claim is:

1. In a filling stop motion for a loom hav-

ing a lay, a filling fork movable relatively to the lay from non-detecting to detecting position as the lay moves forwardly and normally weighted to fall by gravity, means exerting a relatively heavy but variable force acting on the fork when the latter is in non-detecting position and tending to move the fork toward detecting position, and means to reduce said force at the same point in the cycle of the loom independent of the degree of the relatively heavy force so that the force acting on the fork and tending to move the same toward detecting position is relatively light as the lay nears the limit of its forward movement.

2. In a filling stop motion for looms, a system of moving parts including a filling detecting element normally weighted to fall by gravity, a dagger carrying element and a connecting member to cause the elements to move together, and means to exert a yielding force on some part of the system tending to move the detecting element from non-detecting to detecting position during the first part only of the movement of the detecting element toward detecting position, said means effective at the same point in the cycle of the loom independently of the amount of the force exerted by the means.

3. In a filling stop motion for looms, a filling fork element, a dagger carrying element, a connector operatively related to both elements causing the same to move together, a weight operatively related to the connector and movable relatively to the latter and tending to move the detecting element toward detecting position, and means to arrest said weight as the detecting element nears the end of its detecting stroke, whereby said detecting element moves at the end of its detecting stroke independently of the weight.

4. In a filling stop motion for looms, a detecting element movable from non-detecting to detecting position, a dagger carrying element, an elongated connector operatively connecting said elements and causing the same to move together, a weight surrounding said connector and acting on the same when the detecting element is in non-detecting position tending to move said detecting element toward detecting position, and a stop to engage the weight as the detecting element nears the end of its detecting stroke to render said weight ineffective to cause movement of the detecting element as the latter nears the end of its detecting stroke.

5. In a filling stop motion for a loom having a lay, a filling fork in non-detecting position when the lay is in rearward position, gravity actuated means exerting a force tending at all times to cause the fork to fall, additional means to exert a second force on said fork tending to move the same toward detecting position as the lay advances, the combined forces tending to move the fork toward

detecting position, and means to lessen said combined force at a given point in the cycle of the loom and independent of the degree of the second and given force.

6. In a filling stop motion for a loom having a lay, a filling fork in non-detecting position, and means to exert two different forces on said fork tending to move the same toward detecting position as the lay advances, one of said forces being always the same and the other which at a given point in the cycle is completely removed from action, the combined forces being variable in amount, one force being exerted at a given point in the cycle of the loom independent of the amount of the other force as the fork nears the end of its movement toward detecting position.

7. In a filling stop motion for a loom having a lay, a filling fork in non-detecting position, and means to exert two distinct forces on the fork tending to move the latter toward detecting position as the lay advances, one of the forces being always operatively related to the fork, and the other at a given point in the cycle being completely removed from action as the fork nears the limit of its detecting movement at said given point in the cycle of the loom independent of the pressure exerted by said first force, so that only one of said forces acts on said fork as the latter nears the end of its detecting stroke.

8. In a filling stop motion for a loom, a pivotally mounted filling fork element, a pivotally mounted dagger carrier, a connector between said element and carrier to cause them to move together, said fork element, carrier and connector constituting a weighted mass normally tending to cause the fork to fall by gravity, a weighted device movable relatively to the connector, said mass and device effective to tend to move the fork element toward detecting position when the element is in one angular position, and means effective at a given point in the cycle of the loom independent of the amount of the weighted mass and device to render said device ineffective to move the fork element when the latter is in another angular position, the combined weight of the mass and device being variable.

9. In a filling stop motion for looms, a filling fork element movable from the non-detecting to detecting position, a dagger carrier member, a connector between the element and the member to cause said element and member to move together, said fork element, carrier, and connector constituting a weighted mass normally tending to cause the fork to move to detecting position, a weighted device operatively connected to the connector when the detecting element is in non-detecting position and tending to move said detecting element toward detecting position, and means effective at a given point in the cycle of the loom independent of the amount of the weighted mass and device to render said de-

vice ineffective to move the element when the latter is in another angular position, the combined weight of the mass and device being variable.

5 In testimony whereof I have hereunto affixed my signature.

MICHAEL H. FEEHAN.
